D 20069

UNITED STATES PATENT OFFICE.

CHARLES P. WHITE AND RICHARD E. WARNER, OF TAUNTON, MASSACHUSETTS.

DESIGN FOR A COOKING-STOVE.

SPECIFICATION forming part of Design No. 20,069, dated July 29, 1890.

Application filed April 1, 1890. Serial No. 346,244. Term of patent 14 years.

To all whom it may concern:

Be it known that we, CHARLES P. WHITE and RICHARD E. WARNER, of Taunton, in the county of Bristol and State of Massachusetts, 5 citizens of the United States, have invented and produced a certain new and original Design for Cooking-Ranges, of which the following is a specification.

The accompanying photograph shows in 10 perspective a cooking-range to which our design has been applied, and is believed to illustrate the same fully.

The leading features of our design consist in ornamentation of a novel and artistic character, as will be hereinafter more fully set forth, applied to panels upon the doors and walls of a range, and also of a novel ornamentation of the base of such a range harmonizing with the design of the panels and 20 surfaces.

The principal feature of the design is the combination, with a surrounding border of balls or bosses and included fluted work, of a central diamond-shaped outline, which is represented at A upon the panel B in the photograph as applied to the door of the oven of the range. The same diamond-shaped design will be observed at A' as forming the center of the panel upon the door B', (shown in the 25 photograph,) and at A² as forming the center of the panel B² at the "fire end," so called, of a range. The diamond figure is also repeated in the ornamentation of the base, as shown at A³. The center of the diamond A A' A² is 30 filled, as shown, with an appropriate scroll-work. Surrounding the diamond and forming the border in each case are lines of balls or bosses. These are seen at b, b', b², and b³. Upon the panels A, A', and A² flutes C lead 35 40 inwardly toward the center of the panel, and

portions of the border may be formed by shell-like figures D, as shown at A and A'. In the main panel, or that one upon the door B, the central design is surrounded with floriate work E within a plain raised band. The base 45 also, in addition to the diamond design and border of bosses, is provided with ornamental corners F, formed of a combination of scrolls with the flutes and bosses, and beneath these 50 corners other flutes G lead downward to the usual inwardly-curved feet.

We claim—

1. The design for a door or panel of a range herein shown and described, the same comprising an interior diamond-shaped figure A, 55 a border of balls or bosses b, and interposed fluted work C.
2. The design for the base-panel of a range, as herein shown and described, the same comprising an interior formed of diamond-shaped 60 open-work portions A³, with a border of balls or bosses b³, and corner portions formed of balls, scrolls, and fluted work G, descending below the same.
3. The design for a range herein shown and 65 described, the same comprising central figures A, A', and A², arranged upon panels B, B', and B², bordering of balls or bosses b, fluted work C, and shell-formed portions D of the base-panels A³, with their borders b³, and corner designs composed of balls, flutes, and scrolls F 70 and fluted portions G, as set forth.

In testimony whereof we have hereunto subscribed our names this 17th day of March, A. D. 1890.

CHARLES P. WHITE.
RICHARD E. WARNER.
